CLAIM

The ornamental design of a disposable support for a disposable bed pan, as shown and described.

DESCRIPTION

FIG. 1 is a top plan view of a disposable support for a disposable bed pan showing my new design;
FIG. 2 is a bottom plan view thereof;
FIG. 3 is a front elevation thereof;
FIG. 4 is a rear elevation thereof;
FIG. 5 is a side elevation thereof; and
FIG. 6 is a cross section taken on line 6—6 of FIG. 3.
